Attorney

UNITED STATES PATENT OFFICE.

ALBERT DUKE, WILLIAM H. ALLSOP, AND ALBERT MEDFORD, OF GRACE, IDAHO.

VENTILATING CAN LID.

Application filed March 2, 1926. Serial No. 91,756.

Our present invention has to do with can lids, and one of its objects is the provision of a peculiar and advantageous ventilating lid.

5 Another object of the invention is the provision of a can lid of ventilating type that is self-adjusting and is therefore adapted to fit tightly, of itself, when inserted in a can mouth.

10 To the attainment of the foregoing, the invention consists in the improvement as hereinafter described and definitely claimed.

In the accompanying drawings, forming part of this specification:—

15 Figure 1 is a fragmentary elevation of a can with the lid constituting the best practical embodiment of our invention of which we are aware positioned in the mouth of the can.

20 Figure 2 is an enlarged perspective of our novel lid per se.

Similar numerals of reference designate corresponding parts in both views of the drawings.

25 The can 1 illustrated is provided with a mouth 2 and is otherwise of the ordinary well known construction.

Our novel lid is provided with a top 3, and a handle 4, and is also provided with a

30 flared upper annular portion 5 which is designed when the pendent portion of the lid is inserted in the mouth 2, to prevent dirt from dropping into the said mouth. The chief feature of our invention resides in an

35 annular skirt 6 of sheet metal appropriately connected with and pendent from the top 3. The said skirt 6 has upper end portions lapped as designated by 7 and connected together by rivets 8, and the skirt also has

40 lapped, lower end portions 9 which are not connected together, and consequently the lower portion of the skirt is self-adjusting, and is adapted to be tightly crowded into the mouth 2 so that the frictional contact be-

45 tween the skirt 6 and the mouth 2 may be depended upon to preclude casual movement of the lid with respect to the mouth 2. This will be appreciated as an important advantage when it is understood that for ventilating purposes the lid is positioned in the mouth 2 with the marginal flange or portion

50 spaced above the upper end of the mouth 2.

55 For ventilating purposes the annular skirt 6 is provided with spaced upright slots 10, the ends of the said slots 10 being preferably

rounded as illustrated to facilitate thorough cleaning thereof. The slots 10 extend in series entirely around the skirt 6, and in the preferred embodiment of our invention we also employ in the skirt 6 upper apertures 11, 60 the said apertures 11 being, by preference, arranged in vertical alinement with the slots 10, and one aperture 11 to each slot 10.

It will be readily understood from the foregoing that when our novel lid is pressed down in the mouth 2 to the full extent, the flared flange or marginal portion 5 by co-

operation with the upper edge of the mouth 2 will effectively close the can and exclude atmospheric air therefrom. When, how- 70

ever, the lid is positioned in the mouth 2 so that portions of the slots 10 and the aper- 75

tures 11 are exposed to the atmosphere, it will be manifest that the lid will adequately ventilate the can, the amount of ventilation 75

depending upon the extent to which the skirt portion of the lid is moved downwardly into the mouth 2. In this connection it will be noted that when but very little ventilation is 80

desired, the skirt portion 6 of the lid is moved downwardly into the mouth 2 to such

an extent that the apertures 11 alone are ex- 85

posed above the upper edge of the mouth 2.

The skirt 6 of our novel lid being formed of appropriate sheet metal, it follows that notwithstanding the foraminous character of the said skirt 6, the skirt is well adapted to withstand the usage to which the skirts of cream can lids and the like are ordinarily subjected. It will also be manifest that the 90 lid characterized by the foraminous sheet metal skirt is but little more expensive than lids having pendent portions of skirts of im- 95

perforate character.

We have entered into a detailed descrip- 95

tion of the construction and relative ar- 100

angement of the parts embraced in the pres- 105

ent and preferred embodiment of our inven- 110

tion in order to impart a full, clear and exact

understanding of the said embodiment. We

do not desire, however, to be understood as

confining ourselves to the precise construc-

tion disclosed, our invention being defined by

our appended claims within the scope of

which structural changes and changes in

relative arrangement may be made without

departure from our invention.

Having described our invention, what we

claim and desire to secure by Letters-Pat-

ent, is:—

1. A ventilating can lid comprising a top, an upwardly extending outwardly flared marginal flange thereon, a handle on the top, and an annular skirt portion of sheet metal carried by and pendent from the top and having upper lapped end portions connected together and also having lower lapped end portions free to move with respect to each other, and further having in its lower portions foramina for ventilating purposes.
2. A ventilating can lid comprising a top, an upwardly extending outwardly flared marginal flange thereon, a handle on the top, and an annular skirt portion of sheet metal carried by and pendent from the top and having upper lapped end portions connected together and also having lower lapped end portions free to move with respect to each other, and further having in its lower portions foramina for ventilating purposes; the said foramina in the lower portions of

the skirt including spaced upright slots extending in series entirely around the skirt.

3. A can lid having a pendent annular skirt portion, the upper portions of the ends of which are lapped and connected together and the lower portions of the ends of which are lapped and free to move with respect to each other and also having in the lower portions of the skirt foramina for ventilating purposes.

4. A can lid having an annular skirt portion of sheet metal, the upper portions of the ends of the sheet metal being lapped and connected together, and the lower portions of the ends of the sheet metal being lapped and free to move with respect to each other.

In testimony whereof, we affix our signatures.

ALBERT DUKE.

WILLIAM H. ALLSOP.

ALBERT MEDFORD.
